UNITED STATES PATENT OFFICE.

JULES FRITSCH, OF PARIS, FRANCE.

LANDING GEAR.

Application filed October 21, 1926, Serial No. 143,122, and in Belgium October 26, 1925.

This invention relates to landing gear adapted for use in connection with land or sea-planes.

One of the objects of the invention is to provide a landing apparatus that diminishes to a minimum the possibility of overturning or capsizing during a landing operation.

Another object is to provide a landing gear capable of rectifying the position of the aeroplane when the plane lands "nose-down".

A further object is to provide landing apparatus which enters into action only during an abnormal landing and which is capable of exerting a yielding resistance to landing shocks which might otherwise damage or destroy the machine.

Still further objects will appear in the course of the detailed description which will now be given, reference being had to the accompanying drawings in which:—

Fig. 1 is an elevation of one form of landing gear with the wheels in the flying and "taking-off" position.

Fig. 2 is a plan of the apparatus shown in Fig. 1 as seen from 2—2.

Fig. 3 shows an aeroplane landing nose down on the gear illustrated in Figs. 1 and 2.

Fig. 4 shows in elevation a second form of landing gear.

Fig. 5 is a plan view of the apparatus shown in Fig. 4 taken on line 5—5.

Fig. 6 illustrates a third form of the invention with the aeroplane in "taking-off" position as in Fig. 1.

Referring to the various figures of the drawing, there is shown a landing gear comprising (1) the usual type of landing assembly, i. e., a pair of landing wheels *a* supported on a transverse shaft or axle *b* which is connected by a shock-absorber (not shown) to longitudinal elements *c* rigidly connected to chassis *d*; chassis *d* is guided in its movements in any convenient way;

(2) a pivoted system coupled to (1) and arranged symmetrically with respect to the aeroplane axis. The pivoted system (2) may be constructed in a variety of ways.

In the modification shown in Figs. 1 to 3 it comprises longitudinal levers *e* pivoted, at points located between wheels *a* to members integral with transverse element *c*. Levers *e* are connected at their rear ends to fuselage *h* by means of elastic shock-absorbers *i*.

At their front ends they carry wheels *g* mounted on axle *f*. Wheels *g* may be of

smaller diameter than wheels *a* and should be located in front of a vertical line, passing through the center of gravity of the machine. In Figs. 4 and 5 the pivoted system (2) includes a bent lever *e¹* pivotally connected to chassis *d* at points *e²* located in front of axle *b*, a second bent lever *e⁴* pivotally mounted on the chassis rearwardly of axle *b* at *e⁵*, elastic shock absorber *i* similar to those shown in Figs. 1 to 3, and an adjustable cable or link *e³* connecting the free ends of the bent portions of levers *e¹* and *e⁴*. The third form of pivoted system shown in Fig. 6 comprises a bent lever *e¹* mounted in the manner described in connection with the modification represented in Figs. 4 and 5, said lever being connected directly to a shock absorbing assembly *i*, *l* extending from *e⁶* on lever *e¹* to a point of support on chassis *d* situated rearwardly of axle *b*.

Wheels *g* should, preferably, be mounted on a common axle *f* mounted in any convenient manner (in sockets, for example) on the ends of levers *e* or *e¹*. Levers *e* or *e¹* and axle *f* thus assembled constitute a yieldable or resilient chassis which permits wheels *g* to touch the ground at the same time. This yieldable chassis is held together either by loose connecting elements *j* or by rigid rods mounted at their points of junction in movable sockets. The deformable chassis may be provided with means for maintaining propeller *k* clear of the ground during landing, said means comprising loose cables *l* connected in positions parallel to shock absorbers *i*, said cables serving to limit the distending movement of elements *i* and preventing movement of levers *e* or *e¹* to positions permitting contact between the propeller *k* and the ground. Wheels *g* are held above the ground level during "taking-off" and flight (*a*) by cables *m* connecting levers *e* or *e¹* to arms *d* of the chassis, or (*b*) by means of abutments located rearwardly of the points of articulation of levers *e* or *e¹*.

Landing apparatus constructed in accordance with the foregoing description considerably minimizes the danger of capsizing during a landing operation. When the aeroplane lands "nose-down" auxiliary wheels *g* coacting with shock-absorbers *i* constitute a couple which exerts a turning movement tending to bring the center of gravity of the machine into correct landing position. Similarly, in "taking-off" the risk of capsizing because of imperfect

maneuvering or because the ground is rough is greatly diminished.

It is to be understood, of course, that the invention is not limited to use with land machines. By replacing wheels *a* and *g* with floats the same correcting effects may be obtained in landings effected on water by hydro-aeroplanes.

It is further to be understood that the particular constructions described are not to be taken in a limited sense; levers *e* or *e'* may be replaced by a single lever fitted with a wheel or a float or a skid, or by a large number of levers similarly fitted; shock absorbers *i* may be replaced (*a*) by a pair of telescoping tubes moving against the action of a spring or (*b*) by a piston exerting a cushioning action pneumatically in moving into and out of cylinder or (*c*) by a piston and cylinder moving against a liquid; shock absorbers *i* may be located forwardly instead of rearwardly of levers *e* or *e'*; etc.

What I claim is:-

1. An apparatus of the class described comprising in combination an aeroplane body, a landing chassis, a main landing support associated with said chassis, an auxiliary landing support mounted on said chassis, resilient shock absorbing means associated with said auxiliary landing support, and means associated with said shock absorbing means for limiting the movement thereof relative to said main landing support.

2. An apparatus of the class described comprising in combination an aeroplane body, a landing chassis, a main landing support mounted on said chassis, a lever pivotally mounted on said chassis, an auxiliary landing support mounted on one arm of said lever, resilient shock absorbing means connected to the other extremity of said lever, and means adapted to limit the movement of said shock absorbing means.

3. An apparatus of the class described comprising in combination an aeroplane body, a landing chassis, a main landing support mounted on said chassis, a lever pivotally supported on said chassis, an auxiliary landing support mounted on said lever, flexible means for maintaining said auxiliary landing support clear of the "taking-off" surface during normal "taking-off", resilient shock absorbing means extending from said lever to a fixed part of the aeroplane body, and a flexible cable extending from said lever to a fixed portion of said aeroplane body.

4. An apparatus of the class described comprising in combination an aeroplane

body, a landing chassis, a main landing support associated with the landing chassis, an auxiliary landing support pivotally supported on said chassis, means for maintaining the auxiliary landing support clear of the "taking-off" surface during normal "taking-off", means for absorbing the shocks taken up by the landing support during a landing operation, and means for limiting the pivotal movement of the auxiliary landing support.

5. An apparatus of the class described comprising in combination an aeroplane body, a landing chassis, a main landing support associated with the landing chassis, an auxiliary landing support pivotally supported on said chassis, said auxiliary landing support being located forwardly of a vertical plane passing through the center of gravity of the aeroplane body, means for maintaining the auxiliary landing support clear of the "taking-off" surface during a normal "taking-off", extensible resilient means for absorbing the shock taken up by the auxiliary landing support during a landing operation, and means for limiting the extending movement of said extensible resilient means.

6. An apparatus of the class described comprising in combination an aeroplane body, a landing chassis, a main landing support associated with said chassis, a first lever pivotally supported on said chassis, an auxiliary landing support mounted on said first lever, a second lever pivotally mounted on said chassis, a shock absorbing means connected to said second lever, and means for transmitting the pivotal movements of the first lever to the second lever.

7. An apparatus of the class described comprising in combination an aeroplane body, a landing chassis, landing wheels associated with said chassis, a first lever pivotally supported on the landing chassis, an auxiliary landing wheel mounted on said first lever, said auxiliary landing wheel being located forwardly of a vertical plane passing through the center of gravity of the aeroplane body, means for maintaining the auxiliary landing wheels clear of the ground during normal "taking-off", a second lever pivotally mounted on the landing chassis, shock absorbers connected to the second lever, connecting means extending between movable portions of the first and second levers, and means for limiting the pivotal movement of the second lever.

In testimony whereof I affix my signature.
JULES FRITSCH.
